SOAP DISPENSER

Mac B. Feinson, Brooklyn, N. Y., and William J. Dobkin, Chicago, Ill.

Application March 28, 1939, Serial No. 264,532

2 Claims. (Cl. 221—94)

This invention relates to a soap dispensing device.

It is an object of this invention to provide a soap dispenser which may be operated without touching the device with the hands and without danger of leakage.

It is a further object to provide a dispenser of the character described which will dispense the soap at the level of the hands from a container on the floor by foot action but which, nevertheless, will insure the prompt delivery of soap without dripping or clogging and without the presence of bulky apparatus at the level of the body.

The invention accordingly comprises the feature of construction, combination of elements, and arrangements of parts, which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is a central longitudinal section of an apparatus embodying this invention.

Figure 2 is a top plan view of the same.

Figure 3 is a side elevation of a modified form of the device.

Figures 4 and 5 and 6 are details of the device of Figure 3.

Figure 7 is a section through the pumping mechanism.

Figure 8 is a vertical section through the head construction of Figure 1.

As shown in Figure 1, the device comprises primarily a base 10 within which is carried a soap container 11 adapted to be filled through an opening 12 closed by a cap 13. A vertical hollow post 15 extends upwardly from the base 10 to the height at which it is desired to dispense the soap and on the top of this post is mounted an arm 16 which is rotatable about the axis of the post.

A cylinder 20 is mounted on the base 10 in position to extend into the soap container 11 and substantially to the bottom thereof. Slidable within this cylinder is a piston 21 carrying upon its lower end an expansible washer 22 which is held in place by a screw 23. A spring 24 urges the piston upwardly. The piston has at its upper end an annular channel 25 terminating in an integral collar 26 and above the collar is a further reduced end 27 for operating the piston. A rubber button 28 at the top of the end 27 reduces

noise in its contact between the piston and the operating lever to be described.

A washer 29 surrounds the upper end 27 of the piston. This washer is held between the upper end of the cylinder 20 and a cap nut 30 which at the same time screws down upon the outside of the portion 25 of the cylinder to hold the latter in place and also holds the washer 29 in place to limit the up stroke of the piston by engagement between the washer and the collar 26. A rubber buffer 31 is inserted in the top of the nut 30 to prevent noise if the operating lever should strike the top of the nut. Holes 32 are provided in the top of the cylinder 20 within the soap dispenser in position to permit any soap which creeps beyond the washer 22 into the channel 25 to be discharged back into the container.

The cylinder 20 has an opening 33 in its bottom normally closed by a ball valve 34. This ball is held in place by a suitable cage 35 carried by the spring 24.

In the side of the cylinder there is screwed a nipple 35 carrying a ball valve 36 pressed toward the cylinder 20 by a spring 37 so that the valve 34 permits the soap solution to pass into the cylinder 20 on the upstroke of the piston 21 and the valve 36 permits it to pass through the nipple 35 on the down stroke of the valve.

Attached to the nipple 35 is a coupling 38 for the purpose of facilitating the assembly of the device. This coupling is connected to the arm 16 by a tube 39 carried within the post 15.

The hollow post 15 is preferably screwed into the base 10 as shown at 40 and may be provided with a hollow sleeve 41 surrounding the lower portion of the base. Into the top of the post 15 there is screwed an annular member 42 into which the upper end of the tube 39 is also screwed as shown at 39a so that the tube is firmly supported by the post.

The arm 16 is carried by a head 43 having a depending nipple 44 terminating at its upper end in a shoulder 45. An annular bearing member 46 surrounds the nipple 44 which engages and bears against the shoulder 45. This bearing member 46 is screwed into the top of the post 15 and thus furnishes a bearing support for the head 43. The bearing member 46 has an internal recess 47 in its bottom and within its recess a washer 48 is held by an annular nut 49, thus furnishing a bearing surface against the bottom of the recess 47 which prevents the removal of the head 43 when the bearing member 46 is screwed into the post 15. The bottom surface of the nut 49 engages a packing washer 50 to make a

soap tight joint and the nut 49 has a pair of holes 51 for the purpose of turning the nut upon the nipple 44.

A lever 52 is hinged to the base 10 at 53 and has a foot treadle 54 so arranged as to be substantially at the floor level when the piston 20 is at the bottom of its stroke and to rest above the floor level only so far as is necessary to allow the piston to make its full upward stroke so that the treadle 54 may be easily depressed by raising the toe without taking the weight off the heel.

In the form of the invention disclosed in Figure 3 the base 10 and the dispensing arm 16a are connected by a flexible tube 55 connected at 56 with a Monel metal tube 57, but these are not housed within a post such as 15 but are carried by suitable supports as for example by cleats 58 attached to the wall. In this embodiment the arm 16a is provided with a downwardly extending head 59 having a reduced portion 60 fitting within an opening 61 in stud 62 supported upon the wall by any suitable mechanism such as that described in my co-pending application Serial #236,880, filed October 25, 1938.

This reduced portion 60 is provided with openings 63 which communicate with an annular recess 64 within the stud 62 which in turn communicates with the tube 57 by means of a bore 65.

In the form of the invention disclosed in Figure 4 the tube 57 connects the soap tank, not shown in this figure, with the dispenser arms 16b which is swiveled as shown at 72 with the same construction as that shown in Figure 1. In this figure, however, the arm 16b and head 43b are not supported by a post extending from the tank but are carried by suitable supporting means from the wash basin itself.

As shown there is provided a conical washer 74 bearing at its lower end against the wash basin and having its upper end supporting a flange 75 upon the upper end of a stub post 76 which, insofar as the swivel is concerned, performs the same function as the post 15 of Figure 1. This post 76, however, is short, extending only far enough below the wash basin to receive the nut 77 to hold the parts in place.

Since certain changes may be made in the above construction and different embodiments of the invention could be made without departing from the scope thereof, it is intended that all matter contained in the above description or shown in the accompanying drawings shall be

interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described our invention, what we claim

10 as new and desire to secure by Letters Patent, is:
 1. A soap dispenser comprising a container for a soap solution adapted to rest upon the floor and being confined to a space closely adjacent to the floor, a pump mechanism upon said container, 15 a treadle so positioned as to be operable by the toe without raising the heel from the ground and connected to operate said pump, a horizontal discharge tube at substantially the height of the hands, a support of tubular form extending 20 from said container substantially to the height of said discharge tube and means for rotatably supporting said tube from said support and means for connecting said tube to receive a soap solution from said pump, said means being constructed and arranged to conduct said solution through said tubular support independent of said support.

2. A soap dispenser comprising a soap container, a cylinder extending within said container, a piston adapted to work within said cylinder and having a portion extending outside of said container, there being an inlet and an outlet opening with said cylinder below said piston, valve means for controlling each of said openings, said 30 piston and valves being constructed and arranged to admit liquid soap from said container to said cylinder and to force the same out of said outlet as said piston is reciprocated within said cylinder, said piston having a working portion substantially fitting said cylinder and having a circumferential groove above said working portion to provide a chamber adjacent to the cylinder walls, outlets through said cylinder connecting said chamber with the interior of said container when said piston is substantially at the top of 35 its movement and means tightly surrounding said extending portion of said piston and forming with it and the walls of said container a tight compartment to prevent the passage of soap outwardly of said container through said cylinder.
